ELECTRICAL RECEPTACLE

Harvey Hubbell, Jr., Bridgeport, Conn.

Application January 30, 1936, Serial No. 61,501

2 Claims. (Cl. 173—330)

This invention relates to new and useful improvements in electrical receptacles or connectors.

An object of the invention is to provide an electrical receptacle or connector adapted to take or receive a wide variety of blade contacts.

Another object is to provide a receptacle or connector as indicated in the preceding paragraph wherein provision is made for locking certain types of blade contacts against casual withdrawal from the receptacle or connector.

Other objects and advantages will become apparent from a consideration of the following detailed description taken in connection with the accompanying drawings wherein satisfactory embodiments of the invention are shown. However, it is to be understood that the invention is not limited to the details disclosed but includes all such variations and modifications as fall within the spirit of the invention and the scope of the appended claims.

Throughout the specification and claims I shall use the term "receptacle" as meaning either a receptacle or a connector to receive the contact blades of attachment plug caps.

In the drawings:

Fig. 1 is a top plan view showing by way of example a duplex receptacle constructed according to the present invention but the invention is equally adapted for use in a single receptacle or connector;

Fig. 2 is a view partly in side elevation and partly in section as indicated by the line 2—2 in Fig. 1;

Fig. 3 is a detail sectional view taken substantially along the plane of the line 3—3 of Fig. 1;

Fig. 4 is a bottom plan view of the receptacle of Fig. 1 but with parts broken away to show interior construction;

Fig. 5 is an enlarged detail sectional view taken substantially along the line 5—5 of Fig. 4;

Fig. 6 is a detail view taken as though looking from the right in Fig. 5;

Fig. 7 is an enlarged plan view of a receptacle contact and in section showing a curved blade contact in engagement with the receptacle contact;

Fig. 8 is a view similar to Fig. 6 but showing one of a pair of parallel blade contacts in engagement with a receptacle contact;

Fig. 9 is a plan view of a receptacle contact and showing in section a parallel blade contact in engagement therewith;

Fig. 10 is a sectional view taken substantially along the plane of the line 10—10 of Fig. 9;

Fig. 11 is a top plan view of a modified construction of receptacle a part being broken away to show contact construction;

Fig. 12 is an enlarged sectional view taken substantially along the plane of the line 12—12 of Fig. 11;

Fig. 13 is a detail view showing a curved blade contact in engagement with a contact of the receptacle of Fig. 11;

Fig. 14 is a sectional view taken substantially along the line 14—14 of Fig. 13;

Figs. 15 through 24 are detail views showing various forms of attachment plug cap contact blades.

Referring in detail to the drawings and at first particularly to Figs. 15 through 24, at 10 in Figs. 15 and 16 there is shown a portion of a standard attachment plug cap having parallel 20 contact blades 11 provided in the usual manner with holes or openings 12. Figs. 17 and 18 show a portion 13 of a plug cap including transversely curved contact blades 14 and 14a also provided with openings 15. The lower portions of these 25 blades are laterally expanded providing portions 16 the upper edges 17 of which are straight across. It is also noted that one of the blades as blade 14a is expanded toward one side as shown at 18b so that it is wider than the other 30 blade so the cap is polarized, and if desired the opposite side or edge may be inclined as at 18.

Figs. 19 and 20 show a cap portion 19 carrying contact blades 20 each including a wing or plate-like extension 21 arranged angularly with 35 relation to the vertical or main body portion of its blade. This type of blade is more or less "special" and in this specification and in the annexed claims is referred to as an angular contact blade. In Figs. 21 and 22 there is shown

a portion 22 of a cap including aligned or tandem contact blades 23 each as usual provided with an opening 24. It is noted that the blades 23 while flat as in the case of the blades 11 are arranged at right angles to the blades 11. Figs. 40 23 and 24 show a portion 25 of a cap including T-shaped contact blades 25a having openings 24a therein and blades 25a are in effect a combination of the parallel and aligned blades above referred to. The caps of Figs. 15, 16 and Figs. 45 21 and 22 are standard caps, while the others were originally designed for use with special receptacles.

Referring now to Figs. 1 through 10, at 26 is shown the insulating body of a double or du- 55

plex receptacle. This is shown merely by way of example as the invention is equally adaptable to a single receptacle. Within the body adjacent each of its ends are pairs of recesses 27 and 28 separated by partitions 29. Contacts 30 are arranged in the recesses 27 while similar contacts 31 are arranged in the recesses 28. A mounting strap 32 of conducting material has the contacts 30 mounted thereon while a similar strap 33 mounts the contacts 31. Screws 34 pass through the straps 32 and 33 and the body 26 and plates 35 at the front side of the body and serve to secure the straps in place and function in like manner for the plates 35 which carry 15 binding post 36 as shown.

The recesses 27 and 28 open through the rear of the body 26 and after the contacts 30 and 31 are in place a sheet 37 of insulating material is positioned to cover the straps 32 and 33 and to 20 close the inner ends of the recesses. Such sheet is guided by pins 38 passing through the sheet and the sheet is held in place by a separable screw fastener 39 (see Fig. 3) passing through the sheet, a receivable mounting strap 40, and 25 the receptacle body 26.

As here shown the receptacle body 26 includes an integral front wall 41. However, it is to be understood that the invention is not limited to such a construction as the body may include a 30 removable front cover member having contact blade entrance slots therein.

In its front wall 41 the receptacle is provided with slots 42 and 43 leading into the recesses 27 and 28 respectively and it is noted that the slots 35 are so arranged that one slot 42 and one slot 43 together constitute a pair. Each of the mentioned slots includes a curved portion 44 and a short branch 45 entering the curved portion through the convex side thereof. These slots 40 comprise entrance openings for the insertion of contact blades into engagement with the contacts 30 and 31 within the receptacle.

The curved portions 44 of a pair of slots are so located relatively and are of such length as to 45 permit of the insertion through them of plug cap blades which are parallel, curved or angular as shown in Figs. 15 through 20. Branches 45 of the slots are so located as to provide for the insertion of aligned plug cap blades shown in 50 Figs. 21 and 22, and such branches together with the adjacent parts of the curved portions of the slots provide for the insertion of the T-shaped contact blades shown in Figs. 23 and 24. It will 55 therefore be apparent that the slots constructed as shown are adapted to take a variety of blades in addition to the blades of the standard caps of Figs. 15 and 16, and Figs. 21 and 22.

The contacts 30 and 31 are of the same construction but when mounted in the body are reversed with respect to one another, and it is thought that a detailed description of one will be sufficient for both. Taking contact 30 as an example and referring particularly to Figs. 5, 6 and 7 it is seen that the contact comprises a loop including a pair of arms 46 and 47 connected by a portion 48 and having their upper portions 49 and 50 extending in opposed or parallel relation whereby to receive a contact blade between them. On their inner edges the portions 49 and 50 carry 65 curved wings 51 and 52 respectively. These wings are preferably struck from the same center and extend away from one another as most clearly shown in Fig. 7.

Each receptacle contact also includes an arm 75 53 having a portion 54 extending between the

arms 46 and 47 and disposed on the before mentioned connecting portion 48. A rivet 55 secures the arm 53 to the connecting portion 48 and secures both parts of the contact to the carrying bar 32. The upper portion 56 of arm 53 is laterally extended and is curved, and as shown best in Fig. 7 is arranged opposite the wings 51 and 52 and particularly the latter, although as shown it extends to overlap both of them and thus extends across the gap between them. 10

The curved contact part 56 is spaced from the wings 51 and 52 thereby providing a curved space for the reception of a blade contact. Both portions of the receptacle contact are of spring metal so that an inserted blade will be yieldingly engaged by both of the portions 49 and 50 or the portion 56 and either or both of the wings 51 and 52, depending on the shape of the inserted blade. Curved contact portion 56 carries a lug or protuberance 57, which as shown in Fig. 10 is lanced and pressed therefrom, extending in the direction of the wing 51. For a reason later to be described such lug has rounded sides, but its lower edge 58 is substantially straight across forming a shoulder. 15

The contact containing recesses in the body 26 are larger than the slots leading into them so that portions of the front wall 41 of the body form ledges or shoulders 59 beyond the ends of the slots. This construction enters into the locking of the curved and angular type of contact blades in the receptacle, in engagement with the contacts therein, whereby to prevent casual withdrawal of such blades from the receptacle as will later be fully set forth. 30

When using the receptacle with a cap having curved blades the latter are inserted through the curved portions 44 of the entrance slots and enter between the contact portion 56 and the wings 51 and 52 (see Figs. 5, 6 and 7). Thereafter on 40 turning the cap on the receptacle the extensions 16 of the blade 14 are shifted to dispose their upper edges or shoulders 17 under the shoulders or ledges 59 at the underside of the front wall of the receptacle body so that to withdraw the blades from the receptacle body it is necessary to turn the cap back in the opposite direction to align its blades with the entrance slots and then draw the blades out of the receptacle. The curved portions of the slots are longer than the width of the upper portion of the blade contacts (14c, Fig. 17, or 20a, Fig. 19) so as to permit this relative turning movement between the cap and the receptacle and to permit the blade contacts to slide relative to the receptacle contacts as shown by the dotted and full line positions of Fig. 7. The dotted position shows the position of the blades when inserted into the receptacle and before the turning movement, while the full line position is the position they take after the turning movement and which is the locked position. In unlocking them they are turned back to the dotted position from which they may be withdrawn from the receptacle by pulling straight out on the cap. 50

Also as shown in Fig. 7 when the blades are in the locked positions just described the lugs 57 enter the openings 15 in the blades. Since the sides of the lugs are rounded the blades when being turned may engage and cam the lugs and 70 portions 56 outwardly so that the blades may pass in either direction laterally of the lugs. However, the lower edges 58 of the lugs are straight across or abrupt and any attempt to pull the blades out will be resisted by the lower edges of 75

the lugs engaging the lower walls of the holes in the blades.

A parallel blade cap may be connected with the receptacle by inserting its blades into the curved portions 44 of the entrance slots either midway the ends of such portions or toward either end thereof. If the blades are inserted in the dotted position of Fig. 9 and then the cap turned on the receptacle to shift the blades to the full line position of Figs. 8, 9 and 10 the lugs 57 will enter the holes 12 of the parallel blades to secure them in the receptacle. Turning movement of the cap in the opposite direction will shift the blade to the dotted line position of Fig. 9 and the blades may then be drawn out of the receptacle, the blade in each case having a camming action on the curved or inclined side walls of the lug 57 to push it laterally to permit these movements. The curved portions 44 of the entrance slots are wider than the contact blades to permit this movement. These straight blades of the standard cap may be forced directly into the locked position but in ordinary operation as they are inserted into the slots the curved walls 25 of the lugs 57 tend to direct them to one side or to the unlocked position shown in dotted lines and if it is desired to lock them the cap is then given the turning movement.

A cap having the angular blades 20 may also be used with the receptacle 26, and after such angular blades are inserted through the curved portions of the slots the cap may be turned to carry the wing-like extensions 21 of the blades under the shoulder 59 of the overhanging front wall of the receptacle to secure or lock the blades in the receptacle as in the case of the blades 14 of cap 18.

The receptacle having the slots 42 and 43 will also take the aligned blades 23 and the T-shaped blades 25a. The aligned blades enter through the branches 45 of the slots and pass between and into engagement with the contact portions 49 and 50. In like manner the aligned portions of the T-shaped blades enter the branches 45 of the slots and between the portions 49 and 50 of the receptacle contacts, while the parallel portions of such blades enter the curved slot portions 44 at the juncture of the branches therewith and engage portions 51, 52 and 56 of the receptacle 50 contacts.

With reference to Fig. 1 it will be noted that the curved portion of slot 42 is somewhat longer than the corresponding portion of slot 43. Likewise in Figs. 17 and 18 the expanded portion 14b of one blade 14a is larger than that of the other as previously stated. In this way polarization may be effected as the wider blade 14b cannot be inserted in the shorter slot 43.

Referring to the modification of Figs. 11 through 14, at 60 is shown the insulating body of a single receptacle. Said body is provided with spaced recesses 61 within which are located contacts 62 mounted on straps 63 secured by screws 64 of which one engages a lug 65 carrying a binding post 66. The contacts are passed into the recesses through the inner ends thereof, and in the front wall of the body are a pair of slots 67 leading to the respective contacts 62.

Each slot 67 includes a main or elongated portion 68, bent intermediate its ends so as to include angularly related parts, and a branch 69 enters the portion 68 but is directed outwardly thereof. The contacts 62 each include a metal strip bent to provide an intermediate connecting portion 70 and upwardly or outwardly directed arms 71 and

72 having their upper or outer end portions turned in and providing blade contact engaging portions 73 and 74.

An arm 75 (Fig. 13) has a portion against the connecting portion 70 above mentioned and a rivet 76 passing through said portions and the strap 63 secures them together and to the strap. Arm 75 includes an upwardly or outwardly extending portion 77 the end of which is inturned providing a spring contact blade engaging portion 78 arranged opposite the inner edges of the portions 73 and 74.

From one vertical edge of the portion 78 a wing-like portion or member 79 extends in angular relation to said portion. It is noted in Fig. 14 that the angular relationship between portion 78 and the wing 79 corresponds to the angular relationship between the parts of the elongated slot portion 68.

The contacts 62 are so arranged within the body that the space between the contact portions 73 and 74 aligns with the branches 69 of the entrance slots while the portions 78 and the wing 79 are located in alignment with the angular portions 68 of the slot to be engaged by blade contacts inserted through this angular portion 68 of the slots. As shown best in Fig. 12 contact portion 73 has a small portion or bump 80 pressed therefrom and extending toward the portion 74.

In the use of the receptacle parallel blades 11 may be inserted through either part of the angular slot portion 68 either to engage the wings 69 of the respective contacts or to engage the contact portions 78 together with the portions 73 and 74. The curved blades 14 may be inserted to engage the contact portions 73, 74, 78 and 79 as shown best in Fig. 14 and after such blades are inserted the cap may be turned on the receptacle to bring the upper edges 17 of the 40 blade extensions 16 under the front wall of the receptacle body to lock the blade against casual removal from the receptacle, the angular portions 68 being of sufficiently greater length than the width of the upper portions of the blades to 45 permit this.

Also the angular blades 20 may be inserted through the angular slot portions 68 to engage all of the contact portions 73, 74, 78 and 79. After insertion of the blades 20 cap 19 may be 50 turned on the receptacle to bring the upper edges of the blade extensions 21 under the front wall of the receptacle to lock the cap and receptacle together, as the slots are of greater length than the width of the upper portion of these blades. 55

The aligned blades 23 may be inserted through the branches 69 of the slots and when so inserted enter between and are engaged by the contact portions 73 and 74. When such blades 23 are in the receptacle the lugs or bumps 80 on the portions 73 enter the openings 24 in the blades. The T-shaped blades 25a are inserted as shown in Fig. 12 and their aligned portions function as the aligned blades 23 while their parallel portions function as do the parallel blades 11. 65

Having thus set forth the nature of my invention, what I claim is:

1. An electrical receptacle comprising an insulating body, contacts within the body, said body having a pair of spaced entrance slots for contact blades leading to the contacts, said slots each comprising a crooked portion and a lateral portion entering said crooked portion and both portions being formed by parallel side walls, and said contacts comprising portions constructed and 75

arranged to coact with aligned contact blades inserted through the said lateral portions of the slots and also laterally yieldable curved portions to coact with any one of parallel, curved and angular attachment cap contact blades inserted through the crooked portions of the slots, said curved portions of the contacts being provided with lugs having inclined sides and a shoulder to engage a side of an opening in the blade contacts to lock the blades against casual separation from the contacts, and said crooked portions of the slots being of sufficient length to permit sliding movement of the blades on the contacts on relative turning movement of the cap and receptacle and by camming action on the sides of the lugs to remove said shoulders from the blades to unlock them.

2. An electrical receptacle comprising an insulating body, contacts within the body, said body having a pair of spaced contact blade entrance slots leading to said contacts, said slots each comprising a curved portion and a straight

lateral branch entering said curved portion, said curved portions forming arcs of the same circle, and said contacts comprising portions constructed and arranged to coact with aligned contact blades inserted through the said lateral branches of the slots and also laterally yieldable curved portions to coact with any one of parallel, curved and angular attachment cap contact blades inserted through the curved portions of the slots, said curved portions of the contacts being provided with lugs having inclined sides and a shoulder to engage a side of an opening in the blade contacts to lock the blades against casual separation from the contacts, and said curved portions of the slots being of sufficient length to permit sliding movement of the blades on the curved portion of the contacts on relative turning movement of the cap and receptacle and by camming action on the sides of the lugs to remove said shoulders from the blade openings.
